UNITED STATES PATENT OFFICE

126,047

DESIGN FOR AN AIR DISTRIBUTOR FOR
VENTILATORS

Franz J. Kurth, New York, N. Y., assignor to
Anemostat Corporation of America, a corpora-
tion of Delaware

Application October 30, 1940, Serial No. 96,200

Term of patent 14 years

To all whom it may concern:

Be it known that I, Franz J. Kurth, a citizen of Germany, residing at New York city, in the county of New York and State of New York, have invented a new, original, and ornamental Design for an Air Distributor for Ventilators, of which the following is a specification, reference being had to the accompanying drawing forming a part thereof and wherein:

Figure 1 is a front elevation of an air distributor for ventilators showing my new design.

Figure 2 is a perspective view thereof.

Figure 3 is a horizontal section through the lower portion of the distributor; and

Figure 4 is a central, vertical section through the distributor.

I claim:

The ornamental design for an air distributor for ventilators, as shown.

FRANZ J. KURTH.
